CLAIM

The ornamental design for a beverage capsule recycler, as shown and described.

DESCRIPTION

1. Beverage capsule recycler

1.1 : Top

1.2 : Front

1.3 : Perspective

1.4 : Exploded

1.5 : Perspective

The element shown in view 1.5 is shown isolated to show aspects of the design that are not visible when combined. The broken lines shown in the drawings depict portions of the beverage capsule recycler that form no part of the claimed design.

1 Claim, 5 Drawing Sheets
